UNITED STATES PATENT OFFICE

2,659,949

MACHINE FOR THE CONTINUOUS CASTING
OF METAL RODS

Ilario Properzi, Milan, Italy

Application November 8, 1951, Serial No. 255,474

3 Claims. (Cl. 22—57.4)

1

Machines for the continuous casting of metal rods are known in which the molten metal is poured into a groove formed in the peripheral rim of a wheel, such rim having a flexible strap wrapped around an arcuate portion thereof to cover the corresponding part of the groove and driven by the motion of said wheel, and said strap being in the form of an endless belt which also passes over a pulley with an axis parallel to that of said wheel. Such a machine is disclosed and claimed in copending application Serial No. 78,372, filed February 25, 1949 in the name of the present inventor. A modification of such a machine, in which the container for the molten metal and the pulley are adjustable about the axis of rotation of the wheel, is disclosed in copending application Serial No. 199,387, filed December 6, 1950, in the name of the present inventor.

It is an object of this invention to provide a machine in which the pouring of the molten metal into the groove in the wheel can be readily controlled.

The molten metal is poured into the groove in the casting wheel from a container, e. g. a crucible, and another object of the present invention is to make the crucible position convenient and particularly suitable. This object is achieved by placing the container to one side of the wheel in such a way that a pouring nozzle of the crucible projects laterally therefrom and is inserted between said wheel and ribbon, close to the contact point of the same ribbon with the wheel, and providing an assembly for effecting an adjustment of this nozzle as required.

In the known machine of this kind, the crucible is placed just above the wheel, between the latter and the band. This arrangement prevents the observation of the level of the liquid metal in the groove. Since it is very important to control the height of this level, various means have been proposed for indicating the level of the molten metal during operation of the machine, in lieu of visual observation. In the machine according to the invention, the level of the molten metal is clearly and easily visible by the operator, because the position of the crucible does not hide the liquid surface in the groove and does not disturb the operator when looking into the groove.

According to a feature of the invention and in order to allow any possible and necessary adjusting movement of the container position, the container is supported to have several degrees of freedom to adjust the nozzle position in relation to the aforesaid groove, and to control the head of molten metal in the container.

2

Another object of the invention is to make use of the gases heating the crucible to avoid the contact between the molten metal that flows out of the nozzle, and the surrounding air, which would otherwise oxidize it. The latter object is achieved by conveying the hot gases through a hollow jacket of the crucible and about the nozzle to form a protective envelope around the issuing metal. In addition the nozzle is consequently directly heated by such gases.

It is a primary aim of the present invention, therefore, to provide a machine having the aforesaid features, making it particularly suitable to the manufacture of metal wires and rods produced by a known system.

An embodiment of the present invention is illustrated, by way of example only, in the accompanying drawings wherein:

Figure 1 is a side elevation of a rod casting machine embodying the features of the present invention.

Figure 2 is a plan view with parts in section of part of the machine, shown enlarged.

Figure 3 is a top plan view of the molten metal container of the machine showing the position of the container in relation to the wheel, and

Figure 4 is a side view, partly in section, of a modification of the molten metal container.

The casting machine illustrated comprises a wheel 1 rotatably mounted on a base 10 about a shaft 2 and driven through a chain 3 from a reduction gear 4 which, in turn, is operated by a motor 5 through a continuous speed gear box 6.

The annular peripheral surface or rim of the wheel 1 is furnished with a groove 7 therein, this being closed by a flexible belt or strap 8 around that part of the wheel rim embraced by said belt. This latter is of endless form and is wrapped around said wheel 1 and a Jockey pulley 9 for maintaining the belt taut. The wheel 1 is cooled in known fashion by water circulating through cavities in the spokes and rim thereof.

The pulley 9 is rotatably mounted on an upstanding arm 11 which, in turn, is rotatably mounted on shaft 2. The upper end of this arm is formed to receive a bearing post, the latter having a cylindrical socket for receiving a spring 12 by means of which the mounting and rotary spindle of pulley 9 are urged upwards in resilient fashion.

The casting metal container, which is in the form of a crucible, is placed laterally of the wheel 1. It consists of outer and inner housings, 13 and 14 respectively, which are spaced 55 from one another to define a jacket 15 wherein

the heating gases are caused to flow. The outer housing or wall 13 has a refractory lining. Molten metal enters the inner housing 14 through a conduit 29 and is then conveyed outwardly through a nozzle 16 which is shaped as is clearly shown in Figures 2, 3 and 4. The jacket 15 is fed by combustion gases passing from suitable gas lines (not shown) through couplers 17; these gases burn in the jacket and pass out through a nozzle 18 surrounding the lower portion of the nozzle 16. Thus an atmosphere of protective gas is formed around the fluent issuing metal, preventing any contact between this metal and the oxidizing ambient atmosphere before its entrance into the groove 7 of the wheel 1. Moreover, the fact that nozzle 16 is heated by the burnt gases helps to keep the issuing metal at the crucible temperature.

Furthermore, owing to the position of the crucible, it is possible to see the liquid level in the groove 7 in wheel 1 by inspecting it from above and the heat transmitted by the crucible does not disturb the operator when he looks into the groove.

The crucible is slidably supported by a supporting member 22 which, in turn, is pivoted at 23 to a frame 23a, the frame being rotatably mounted on shaft 2. Frame 23a has a toothed sector 21 which meshes with a pinion 20, the pinion being rotatably mounted on arm 11 and driven by a hand wheel 19. The crucible support 22 may be rotated about pivot 23 by a driving member 24.

The arrangement of the crucible is such that it can be shifted in more than one way relatively to the machine base. Firstly, it can be rotated about the wheel shaft 2, so as to advance or retract the nozzle to or from its tangential point between the belt 8 and wheel 1. These operations can be effected through the driving hand wheel 19 and pinion 20 which meshes with the toothed sector 21 rigid with frame 23a, the latter being pivoted at axis 2 and having a support 22 carrying the crucible supporting member 22. Thus, by rotating wheel 19, the frame is rotated about axis 2 and the said crucible can be given a movement suitable to cause its nozzle to run circumferentially along the periphery of the wheel 1.

The support 22 together with the crucible may be rotated about the pivot 23, which extends parallel to the shafts of wheel 1 and pulley 9, by operation of a driving member 24, thus causing the nozzle to approach, or be withdrawn from, the wheel in a substantially radial direction.

The support 22 is so equipped as to permit also a movement of the crucible in a direction parallel to the wheel shaft. Such shifting is effected by means of a threaded mandrel 25 carrying members 26, the members 26 having threaded apertures engaging the mandrel and these members being rigidly connected to the crucible which is carried therefrom on support 22.

Suitable means are also provided to enable the position of pulley 9 in relation to wheel 1 to be varied. Hence, the angle comprised between the horizontal and a straight line passing through the pivoting axes of wheel 1 and pulley 9 has to be varied, though within small limits, according to the working characteristics of the metal used. For this purpose a screw mechanism, operable by a hand wheel 27, is provided. This mechanism engages the arm 11 and, by manipulating the hand wheel 27, this arm can be tilted in various directions about shaft 2. A post 28,

rigid with the machine frame, is provided to support the mechanism.

In the modification of Fig. 4, the crucible construction is somewhat simpler, the inner housing 14 being supported on refractory material and no provision being made for the aforesaid heating and protective gases.

Many changes may, of course, be made within the scope of the invention, resulting from a replacement of the described construction, on its parts, by others that are operatively and technically equivalent and fulfill the same purposes.

Having now particularly described and ascertained the nature of my said invention and in what manner the same is to be performed, I declare that what I claim is:

1. In apparatus for the continuous casting of molten metal having a rotatable casting wheel with a peripheral casting groove therein, a pulley rotatable about an axis spaced from and parallel to the axis of rotation of said wheel, and an endless belt looped around said wheel and said pulley and defining an enclosed area with said wheel and pulley therein, with said endless belt contacting the wheel as a closure for said groove to provide a casting mold, the combination with said wheel, pulley and belt including an upstanding arm rotatable about the axis of rotation of the aforesaid casting wheel for supporting the aforesaid pulley, supporting means rotatable about the axis of rotation of the aforesaid casting wheel, a crucible supported on said supporting means and having a nozzle extending therefrom between the aforesaid belt and wheel into the aforesaid casting groove, and means for rotating said supporting means with respect to said upstanding arm about the axis of rotation of the aforesaid casting wheel to move said crucible and said nozzle thereon to vary the position of the nozzle circumferentially along the periphery of said wheel.

2. In apparatus for the continuous casting of molten metal having a rotatable casting wheel with a peripheral casting groove therein, a pulley rotatable about an axis spaced from and parallel to the axis of rotation of said wheel, and an endless belt looped around said wheel and said pulley and defining an enclosed area with said wheel and pulley therein, with said endless belt contacting the wheel as a closure for said groove to provide a casting mold, the combination with said wheel, pulley and belt including an upstanding arm rotatable about the axis of rotation of the aforesaid casting wheel for supporting the aforesaid pulley, supporting means rotatable about the axis of rotation of the aforesaid casting wheel, a crucible supported on said supporting means at one side of the aforesaid casting wheel and having a nozzle extending therefrom between the aforesaid belt and wheel into the aforesaid casting groove, means for rotating said supporting means with respect to said upstanding arm about the axis of rotation of the aforesaid casting wheel to move said crucible and said nozzle thereon to vary the position of the nozzle circumferentially along the periphery of said wheel, and means for rotating said upstanding arm about the axis of rotation of the aforesaid casting wheel to adjust the angular position of said arm.

3. In apparatus for the continuous casting of molten metal having a rotatable casting wheel with a peripheral casting groove therein, a pulley rotatable about an axis spaced from and parallel to the axis of rotation of said wheel, and an end-

less belt looped around said wheel and said pulley and defining an enclosed area with said wheel and pulley therein, with said endless belt contacting the wheel as a closure for said groove to provide a casting mold, the combination with said wheel, pulley and belt including an upstanding bracket rotatable about the axis of rotation of the aforesaid wheel for supporting the aforesaid pulley, an arm rotatable about the axis of rotation of the aforesaid casting wheel, a supporting member pivotally mounted on said arm about an axis spaced from and parallel to the axis of rotation of the aforesaid casting wheel, a crucible supported on said supporting member at one side of the aforesaid casting wheel and having a nozzle extending laterally therefrom between the aforesaid belt and wheel into the aforesaid casting groove, a control means for rotating said supporting member about its pivotal axis on said arm to move said nozzle in a substantially radial direction with respect to the aforesaid wheel, and means mounted on said upstanding bracket and engaging said arm for rotating said arm with respect to said upstanding

bracket about the axis of rotation of the aforesaid casting wheel to move said crucible and said nozzle thereon to vary the position of the nozzle circumferentially along the periphery of said wheel.

ILARIO PROPERZI.
